SHOE LAST CONSTRUCTION

George C. Clark, Beverly Hills, Calif.

Application April 17, 1936, Serial No. 74,885

9 Claims. (Cl. 12—140)

This invention relates to improvements in shoe last construction.

An object is to provide a shoe last wherein a metallic last body is equipped with tacking strips or elements securely embedded therein against detachment therefrom during use of the last.

Another object is the provision of a last having the required tacking elements embedded in the bottom face of the last and securely held in place 10 therein by means formed integrally with the last body and embedded in the tacking elements.

A meritorious feature is the provision of a last body having a tacking element receiving recess wherein a tacking element is seated and the side 15 walls of which recess have integral angular portions projecting interiorly of the recess and embedded in the tacking element. The tacking element receiving recess is preferably so formed that a side wall of the recess carries an acute-angled 20 lug or rib which projects interiorly of the recess and is embedded in the tacking element.

An important characteristic of this rib or lug is that the lower face of the rib is substantially 25 normal to the side wall and the upper face of the rib slopes outwardly toward the side wall and upwardly toward the entrance to the recess whereby a tacking element may be inserted for seating within the recess but once seated therein is securely locked against removal or withdrawal 30 therefrom.

More specifically, the tacking element retaining rib preferably extends linearly of the side wall of which it is an integral part. It is spaced above the bottom of the recess and below the entrance thereto. It has an outer or upper face which slopes downwardly from the side wall to an edge, which lower face is preferably horizontal. It constitutes an acute angle projection which permits insertion of a compressible tacking strip, yet so 35 embeds itself within the tacking strip as to securely lock the same in place.

Other objects, advantages, and meritorious characteristics of this invention will more fully appear from the following description, appended 40 claims, and accompanying drawing, wherein:

Figure 1 is an elevation of a last looking at its bottom face.

Fig. 2 is an elevation of a last partly broken away on the line 2—2 of Fig. 1.

Fig. 3 is a cross-sectional view taken on 3—3 of Fig. 1, and

Fig. 4 is a fragmentary cross-sectional view taken on the same line as Fig. 3 but enlarged and showing the tacking strip removed.

In the figures of the drawing let 10 indicate a

last body which may be formed of suitable metal and provided with the required tacking elements and strips. This invention relates to the locking or securement of the tacking elements in place. It is understood that the last body would carry such number of these elements as was desired and that they would be positioned as desired. These tacking elements are formed of suitable material adapted to receive tacks temporarily held therein to maintain the shoe upper and sole in place during certain steps in the fabrication of the shoe. A suitable composition of rubber material may be employed. Leather may be employed. Such material is penetrable by the tacks and tends to seal itself upon withdrawal of the tacks. Such 15 material is likewise compressible and resilient for insertion within the provided recess.

The bottom face 12 of the last body has a tacking strip receiving recess 14 formed therein. This recess is substantially rectangular in cross section. A side wall of this recess carries a rib or lug 16 which projects into the recess. In the figures of the drawing the opposite side walls of the marginal recess 14 are shown as provided with such ribs. The side wall of the interiorly disposed 25 circular recess has a rib which extends circumferentially therearound as shown in Fig. 3 holding element 18 thereon.

These lugs or ribs are formed so as to have an upper face 20 that slopes from the interior edge 30 outwardly and upwardly toward the side wall. The lower face extends substantially normal to the side wall. The rib forms an acute-angled projection which permits insertion of the tacking strip inwardly into the interior of the recess to seat therein but prevents withdrawal of the tacking strip from such seated position.

The tacking strip itself is indicated as 22. As 35 stated it is formed of compressible resilient normally penetrable material. It has a width substantially equal to the normal rectangular width of the recess. It is inserted as shown in Fig. 3 by being forced inwardly. It is compressed as it rides over the sloping upper faces of the ribs 16 so as to move to a seated position within the recess. When seated the ribs embed themselves within the compressible strip and the horizontal lower faces prevent withdrawal of the strip and securely hold it in place.

It is understood that in the manufacture of 50 shoes the tacks which enter these strips may be of such length that they extend to the bottom of the recess. Certain of them might turn over at the ends. Withdrawal of these tacks exerts considerable pressure tending to withdraw the 55

tacking element from the recess within which it is seated. A locking rib formed as shown herein so engages the tacking element that such accidental withdrawal is prevented and the tacking element retains its position in the recess without the employment of adhesive or other retaining means.

It will be noted that the side walls of the recess as shown are parallel and that the tacking strip has a width substantially equal to the distance between the straight side walls of the recess. The same is true of the tacking elements 18.

What I claim:

1. A shoe last having a bottom face provided with a recess, a tacking element seated therein, said recess having a side wall provided with a lug projecting interiorly of the recess and embedded in the tacking element, said lug having a shoulder engaging the tacking strip below the outer edge of the side wall provided with the lug.

2. A shoe last having a bottom face provided with a recess, a tacking element seated therein, said recess having a side wall provided with an acute-angled lug projecting interiorly of the recess spaced above the bottom of the recess and below the outer edge of the side wall provided with the lug and embedded in the tacking element.

3. A shoe last having a bottom face provided with a tacking element receiving recess having a width across the bottom of the last substantially equal to the width across the bottom of the recess, a tacking element seated therein, said recess having a side wall provided with a linearly extending acute-angled rib projecting into the recess and embedded in the element.

4. A shoe last having a bottom face provided with a tacking element receiving recess, a tacking element seated therein, said recess having a side wall provided with a linearly extending acute-angled rib projecting into the recess and embedded in the element, said rib having a lower face which forms with the side wall of the recess an angle not greater than a right angle.

5. A shoe last having a bottom face provided with a tacking strip receiving recess substantially rectangular in cross-section, a tacking strip seat-

ed therein, each side wall of said recess provided with a linearly extending rib projecting into the recess and embedded in the tacking strip, said rib having a lower face which is substantially normal to the side wall of the recess and an upper face which slopes outwardly toward said wall and upwardly toward the entrance to the recess.

6. A shoe last comprising a body portion having a normally impenetrable bottom face provided with a tacking element receiving recess having a width across the bottom of the last substantially equal to the width across the bottom of the recess, a normally penetrable tacking element normally rectangular in cross section seated within said recess, said recess having a side wall provided with a part formed integrally therewith embedded in said tacking element retaining the same within the recess.

7. A shoe last comprising a body having a normally impenetrable bottom face provided with a tacking element receiving recess having normally parallel side walls, a normally penetrable compressible resilient tacking element seated within said recess, one side wall of said recess having an angular part projecting into the recess and embedded in the tacking element.

8. A shoe last having a bottom face provided with a tacking strip receiving recess substantially rectangular in cross-section, a compressible resilient tacking strip substantially rectangular in cross-section seated in said recess, each side wall of the recess provided with a linearly extending rib projecting into the recess and embedded in the tacking strip, said rib having a lower face which is substantially normal to the side wall and an upper face which slopes outwardly toward said wall and upwardly toward the entrance to the recess, said strip having a normal uniform width substantially equal to that of the recess above the rib.

9. A shoe last having a bottom face provided with a tacking element receiving recess, a tacking element seated therein, opposite side walls of said recess provided with opposed angular lugs embedded in opposite sides of the tacking element below the outer face thereof retaining the tacking element within the recess.

GEORGE C. CLARK.
